POST BINDER

Frank Stanley Schade, Holyoke, Mass., assignor
to National Blank Book Company, Holyoke,
Mass., a corporation of Massachusetts

Application December 27, 1943, Serial No. 515,691

6 Claims. (Cl. 129—12)

This invention relates to improvements in the construction of loose leaf or post binders. As is well understood, these binders are constructed of a pair of cover portions, at least one of which is provided with a hinge and with a clamp device by which it can be held in adjusted position upon posts secured to the other member. It is the object of the present invention to improve upon prior constructions in increasing the degree of flexibility of the hinge, distributing the hinge action over a larger area, and greatly simplifying and cheapening the nature of the hinge construction.

Referring to the drawing,

Fig. 1 is a fragmentary plan of the adjustable member of the post binder;

Fig. 2 is an enlarged section on line 2—2 of Fig. 1; and

Figs. 3 and 4 are respectively end and top views of a plug closure for the adjustable member.

The body of one of the cover members has been shown at 1 in section and without detail since the specific construction of the interior of the cover is immaterial to the present invention. A fabric cover 2 is adhesively secured to the body 1, extends beyond this body portion at one side through a hinge portion 3, around a bead 4, preferably formed of metallic wire, and returns through the hinge portion 3 so as to form the bottom facing 5 of the cover 1. The two layers of the fabric at 3 are preferably adhesively secured together and the length of the free portion of fabric forming the hinge is preferably made great enough so that the hinge action will not be restricted to any particular line but may be distributed over a comparatively wide area of the fabric. The bottom cover member 6 may be constructed in a similar manner to form a hinge, or in some instance where a hinge is not necessary in the bottom cover member other types of construction may be used. In the example shown, the bottom cover member has a hinge 7 provided with a bead 8 and constructed as described above.

The hinge portions are received and held respectively in channel shaped members 9 and 10, forming upper and lower binder tubes. These are conveniently formed from sheet metal bent into channel shape to provide one jaw member 11 and a cooperating jaw member 12 formed by rolling the edge of the channel into a bead of moderately large radius. The straight jaw member 11 is located on that side of the hinge toward which no hinge action will occur or, in other

words, the interior of the cover. The bead 12 serves to permit a rolling action of the flexible hinge 3, constantly changing the fold line of the hinge and avoiding danger of breakage of the hinge portion by reason of repeated flexing along a definite line.

The post construction may be varied as desired since in itself it forms no part of the present invention. As shown, the lower channel 10 has a post 13 arising from it and held as by a plug 14 having a hole in which the end of the post may be received and held either by friction or by the use of a suitable adhesive. The upper member carries post locking mechanism which has been indicated generally at 15 and which may be constructed as described in detail in the patent to John Schade 2,211,517, August 13, 1940. A further description of that mechanism is unnecessary here.

20 In order to avoid complexity in the construction of the tube members, they are preferably left open at the ends, the ends being later closed by plugs shown in Figs. 3 and 4 having a head portion 16 of the same contour as that of the outside 25 of the tube and an extending portion 17 adapted to enter into the end of the tube member and be retained there as by a pin or screw 18. In assembling or disassembling a tube member from the cover it is preferable to expand the tube 30 somewhat at one end as by forcing a tapered plug into it. This moves the jaws 11 and 12 slightly apart and permits the hinge portion 3 to be slid between them with one end of the bead 4 lying behind the jaws. The tapered plug can then be 35 removed whereupon the hinge will be clamped tightly between the jaws in such a way that it cannot be removed except by the use of a considerable sliding force or the deliberate expansion 40 of the tube. The hinge is further sealed in position by the plug members 17 which overlap the ends of the jaws and are held by pins 18. The plugs 17 preferably extend far enough into the tubes so as to lie back of the beads, thereby 45 preventing the latter from sliding rearwardly into the tubes.

It will be seen that as compared with the hinge construction shown in the John Schade patent referred to above, the present construction is of 50 much greater simplicity and has a range of hinge action limited only by the contact of the cover with the ends of post 13. Furthermore the tube members can be readily removed whenever it is desired for the repair or the replacement of the

cover members. The initial assembly operation is also greatly facilitated.

I claim:

1. A loose leaf binder having a cover, a flexible extension of the cover, a bead formed on the edge of said extension, and a channel-shaped binder tube having spring jaws engaging the beaded edge of said extension for the purpose of connecting the cover to the tube in a readily removable manner.

2. A loose leaf binder having a cover, a flexible extension of the cover, a bead formed on the edge of said extension, and a channel-shaped binder tube having jaws engaging the beaded edge of said extension, at least one of said jaws being substantially cylindrical to provide a rolling fulcrum for said flexible extension.

3. A loose leaf binder comprising a cover body, a flexible covering for said body extending beyond the cover body at one edge thereof and enclosing a bead core at the edge of said extension, and a channel-shaped binder tube having spring jaws enclosing said extension adjacent the bead for the purpose of connecting the cover to the tube in a readily removable manner.

4. A loose leaf binder comprising a cover body, a flexible covering for said body extending beyond the cover body at one edge thereof and enclosing a bead core at the edge of said extension, and a channel-shaped binder tube having jaws enclosing said extension adjacent the bead, at least one of said jaws being substantially cylindrical to provide a rolling fulcrum for said flexible extension.

5. A post binder comprising a cover body, a flexible covering for said body extending beyond the cover body at one edge thereof and enclosing a bead core at the edge of said extension, and a channel-shaped binder tube having jaws enclosing said extension adjacent the bead, at least one of said jaws being substantially cylindrical to provide a rolling fulcrum for said flexible extension, and plugs closing the ends of the channel-shaped member.

6. A post binder having a cover member provided with posts, a second cover member provided with means for adjustably engaging said posts, at least one of said cover members having a body, a flexible covering adherently secured to one face of said body and extending beyond it at one edge to form a flexible extension and bent reversely at the end of said flexible extension and adherently secured to the second face of said body, a bead core enclosed by the reverse bend of said flexible covering to form a bead at the end of said flexible extension, a channel-shaped binder tube of resilient material having the edges of the channel bent inwardly to engage the flexible extension beyond said bead, the jaw at the inside surface of the cover being at substantially right angles to the plane of said flexible extension and the opposite jaw being formed by edge portions of the channel portion rolled inwardly into substantially cylindrical form to provide a rolling fulcrum for said flexible extension.

FRANK STANLEY SCHADE.
